UNITED STATES PATENT OFFICE.

BURR B. BLOOD, OF CHICAGO, ILLINOIS, ASSIGNOR, BY MESNE ASSIGNMENTS, OF ONE-HALF TO KINNEY-ROME COMPANY, OF CHICAGO, ILLINOIS, A CORPORATION OF ILLINOIS, AND ONE-HALF TO ROME METALLIC BEDSTEAD COMPANY, OF ROME, NEW YORK, A CORPORATION OF NEW YORK.

BED CONSTRUCTION.

1,161,921.

Specification of Letters Patent. Patented Nov. 30, 1915.

Application filed September 9, 1912. Serial No. 719,330.

To all whom it may concern:

Be it known that I, BURR B. BLOOD, a citizen of the United States, residing at Chicago, in the county of Cook and State 5 of Illinois, have invented certain new and useful Improvements in Bed Construction, of which the following is a specification.

My invention relates to devices for yieldingly supporting a bed bottom on a bedstead frame.

Broadly considered, the object of my invention, generally stated, is to provide a novel and efficient construction of cushioning device for removably and yieldingly supporting a bed bottom on the side rails of the bedstead frame.

More specifically considered, the object of my invention is to provide a device of this kind that can be readily applied to bed bottoms of ordinary and approved form, without materially changing the construction thereof, and without requiring the use of special castings or other parts for the bed bottom frame.

To these and other useful ends my invention consists in matters hereinafter set forth and claimed.

My invention, in one form thereof, is illustrated in the accompanying drawings, 30 in which—

Figure 1 is a perspective elevation of the complete bed construction; and Fig. 2 is a fragmentary detail, enlarged, of the corner portion of the bed-bottom frame and its 35 spring supporting device; Fig. 3 is a transverse section through the bed on line 3—3 in Fig. 1.

Referring to the drawing, 1 and 2 designate, respectively, the head and foot pieces, 40 and 3 the side rails of an ordinary metallic bedstead.

4 designates cross-bars extending between and resting at their ends upon the side rails 3 adjacent to the upper and lower ends of 45 the latter.

5 designates as a whole the bed-bottom, the frame of which comprises essentially transverse end bars 6, preferably made of angle-iron, longitudinal side bars 7, herein 50 shown as tubular in form, and vertically disposed corner brackets 8 connecting said side and end bars.

9 designates the bed-bottom fabric which is stretched between the end bars 6, as usual.

10 designates coil compression springs, 55 which are stepped upon the cross-bars 4 just inwardly of the outer ends of the latter. Through these springs extend tension bolts 11, said bolts also extending through registering holes in the tubular side bars 7 and 60 cross-bars 4. The head of each bolt engages a washer 12 resting upon the upper end of the spring; and the lower end of the bolt, which projects below the side bar 7, 65 is threaded to receive a wing-nut 13.

By reason of the foregoing construction it will readily be seen that the weight of the bed-bottom and of whatever load it may carry is transmitted to the side rails 3 of the bedstead frame through the nuts 13, 70 bolts 11, washers 12, springs 10, and cross-bars 4, the bolts 11 being under tension, and the springs 10 under compression. It will also be noted that by turning the nuts 13 up or down, the springs 10 can be regulated or 75 adjusted to give the desired cushioning effect. It will be still further noted that the described construction does not require any special form or construction of corner bracket, but is applicable to any construction of bed-bottom frame wherein the end and side bars of the frame are so connected 80 that the latter are sufficiently lower than the former to accommodate the cushioning springs.

An important consideration of my invention, it will be seen, is the fact that with this construction each bolt or rod 11 becomes a supporting element, as it receives the weight as a tensil strain thereon, communicated to 90 the lower end thereof by the side bar 7, whereby the bed-bottom frame is hung in position on the springs. In this way, said bolts or other supporting elements 11 are essential for sustaining the weight of the 95 bed-bottom, as well as for guiding purposes, being adapted to perform this combined function in a simple and efficient manner. This, it will be seen, is advantageous, as previously explained, and as will 100 be readily appreciated by those skilled in the art.

From the foregoing it will be seen that the four supporting bolts 11 transmit all of

the weight sustained by the springs, as the structure involves no other medium through which the weight can be communicated to said springs. Furthermore, and by means 5 of the bed bottom frame, the lower ends of said bolts are maintained in fixed relation to each other, whereby their lower ends do not move toward or away from each other, while the springs are in action. At the same 10 time, however, the upper ends of said bolts may yield slightly, in a lateral or horizontal direction, and to an extent depending upon the stiffness of the bolts and the degree of firmness or rigidity with which they are held at their lower ends. Therefore, and with the bolts secured only at their lower 15 ends, a slight yielding action is possible at their upper ends, if necessary, thus preventing the binding action which might result if the upper ends of the bolts were rigidly and positively held against lateral movement.

The form of my invention herein disclosed has some advantages, and may be preferable 25 in some cases, but for the broader purposes of my invention I do not limit myself to the exact construction shown and described.

I claim—

1. In a bed construction, a bed bottom 30 frame, bolts for supporting said frame, disposed vertically at the sides thereof, means provided with portions forming guides in which said bolts move up and down, said means being arranged for supporting the bed bottom on the side rails of a bedstead and being removable upwardly with the bed bottom from the rails, and springs resting on said means and carried thereby on said bed bottom frame and connected to exert 35 their tension upwardly on said bolts to yieldingly support the bed bottom, said bolts transmitting all of the weight sustained by said springs.

2. In a bed construction, a bedstead 45 frame, a bed bottom frame, bolts for supporting said bed bottom frame, disposed vertically at the sides thereof, means resting on the sides of said bedstead frame, provided with portions forming guides in which said bolts move up and down, for supporting the bed bottom on the side rails of the bedstead, and removable upwardly with the bed bottom from the rails, and springs resting on said means, and carried 50 thereby on said bed bottom frame, and connected to exert their tension upwardly on said bolts, serving to yieldingly support the bed bottom, said bolts transmitting all of the weight sustained by said springs, and said means having provisions whereby the guides at opposite sides of the bed are held in position a fixed distance apart.

3. In a bed construction, a bedstead frame, a bed bottom frame, bolts for supporting 60 said bed bottom frame, disposed vertically

at the sides thereof, means resting on said bedstead frame, provided with portions forming guides in which said bolts move up and down, for supporting the bed bottom on the side rails of the bedstead, and removable upwardly with the bed bottom from the rails, and springs resting on said means, and carried thereby on said bed bottom frame, and connected to exert their tension upwardly on said bolts, serving to yieldingly support the bed bottom, said bolts transmitting all of the weight sustained by said springs, each spring coiled around its allotted bolt, and said bolts being held in fixed relation to each other only at their lower ends by engagement therewith the structure of said bed bottom frame, being unengaged thereby at their upper ends.

4. In a bed construction, a bedstead frame, a bed bottom frame, bolts for supporting 85 said bed bottom frame, disposed vertically at the sides thereof, means resting on said bedstead frame, provided with portions forming guides in which said bolts move up and down, for supporting the bed bottom on the 90 side rails of the bedstead, and removable upwardly with the bed bottom from the rails, and springs resting on said means, and carried thereby on said bed bottom frame, and connected to exert their tension 95 upwardly on said bolts, serving to yieldingly support the bed bottom, said bolts transmitting all of the weight sustained by said springs, and said frame having corner castings, together with means entirely independent of said castings for securing the lower ends of the bolts to the sides of the bed bottom.

5. In a bed construction, a bed bottom frame, bolts for said frame, disposed vertically at the sides thereof, supporting members providing guides in which said bolts move up and down, for supporting the bed bottom on the side rails of a bedstead, removable upwardly with the bed bottom from the rails, springs combined with said bolts, seated on said guides, carried thereby on said bed bottom frame, and means engaging said bolts, bearing upon the tops of said springs, serving to compress the springs when the bed bottom moves downward, said members consisting of bars extending transversely of the bed bottom, above the sides thereof, held against relative displacement by said bolts, and having end portions which engage the bedstead frame.

6. In a bed construction, a bed bottom frame, and means for supporting the bed bottom between the side rails of a bedstead, said means having portions projecting laterally from opposite sides of said frame to rest on said rails, and said means including helical springs arranged for compression by downward movement of the bed bottom, said springs being carried by said frame and

permitting the sides of the latter to move below the plane of said rails.

7. In a bed construction, a bed bottom frame and means for supporting the same between the side rails of a bedstead, said means embodying a plurality of transverse bars disposed on said frame and having portions projecting laterally from opposite sides of said frame to rest on said rails, and
10 helical springs carried by said frame and

arranged for compression by downward movement of the bed bottom, said springs being supported by said bars, and arranged to permit movement of the bed bottom sides below said rails.

BURR B. BLOOD.
